US00D458906S

(12) **United States Design Patent** (10) Patent No.: **US D458,906 S**
Kim (45) Date of Patent: ** Jun. 18, 2002

(54) **INVERTER OPERATOR FOR AN ELECTRIC MOTOR**

(75) Inventor: **Jong Goo Kim**, Seoul (KR)

(73) Assignee: **LG Industrial Systems Co., Ltd.**, Seoul (KR)

(**) Term: **14 Years**

(21) Appl. No.: **29/136,110**

(22) Filed: **Jan. 26, 2001**

(30) **Foreign Application Priority Data**

Jul. 27, 2000 (KR) 00-19760

(51) LOC (7) Cl. **13-03**

(52) U.S. Cl. **D13/164**

(58) **Field of Search** D13/110, 122, D13/123, 162, 164; 307/150, 151; 361/622, 702, 703, 79, 809; 318/778

(57) **CLAIM**

The ornamental design for a inverter operator for an electric motor, as shown and described.

DESCRIPTION

FIG. 1 is a perspective view of inverter operator for an electric motor showing the new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.
